OVEN DOOR

Masic Paul, Juneau, Territory of Alaska

Application May 9, 1938, Serial No. 206,932

2 Claims. (Cl. 126—200)

This invention relates to oven doors, and more particularly to a door for the oven of a cooking range or the like, with transparent means included in the door structure, so that the contents of the oven can be readily inspected without opening the door.

A further object is to provide an oven door that includes companion inner and outer members removably associated and cooperating with spacing means for a pair of transparent panels, for securing the panels in spaced relation to each other.

Another object is to provide an oven door that includes illuminating means carried thereby for illuminating the oven, and the latter preferably has a lining of suitable reflecting material to aid in illuminating the interior thereof.

A still further object is to provide an oven door of the character set forth, that is simple in construction, inexpensive to manufacture, and extremely efficient in use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a rear view of the oven door which forms the subject matter of the present invention, with parts broken away and in section.

Figure 2 is a sectional view taken approximately on line 2—2 of Figure 1, looking in the direction of the arrows.

Referring to the drawing in detail, it will be noted that my door is shown as being of elongated rectangular configuration, but it will of course be understood that it is made in any shape suitable for the purpose.

The door includes inner and outer frame members in the form of shells that are interfittingly associated, and the body portion 1 of the outer frame member has formed about the outer edge thereof, an outwardly flared inwardly directed rim 2, while the body portion 3 of the inner frame member has an outwardly flared rim 4 about its edge, the rim 4 being of greater width than the rim 2 and inclined to a less degree, with its edge seated with respect to the body portion 1 at the juncture of the rim 2 therewith, as best shown in Figure 2. A gasket 5 is disposed between the body portion 1 and the edge of the rim 4 and the

gasket is preferably formed from asbestos or other like material, as will be apparent.

The body portions of the frame members have inwardly directed flanges 6 about the openings 7 thereof, to provide shoulders 8, for receiving transparent panels 9 for closing the openings 7, as best shown in Figure 2, and the panels 9 are preferably made from relatively thick glass. The panels may be provided with channel gaskets about the edges thereof, or any suitable gaskets may be used for the panels.

The panels are held seated in the shoulders by a spacing frame 10 that has its outer edges received by the flanges 6 and formed on and inwardly extending from the body portion 1 are 15 lugs 11 having threaded bores for receiving screw bolts 12 that extend through openings in the body portion 3 and cooperate with the lugs for holding the frame members secured together, as well as the panels in spaced parallel relation with respect to each other, through the medium of the spacing frame 10.

The door may be hingedly or pivotally associated with the frame of the oven, by any well known means, but I have illustrated pintles 13 formed on and extending outwardly from the outer ends of the lower portion of the rim 2, to be received in socket members in the frame, as will be apparent, and the rim 2 is engaged with the frame when the door is in closed position.

I also provide illuminating means for the oven, and which is carried by the door, preferably adjacent one corner thereof, as best shown in Figure 1, and the illuminating means includes a base member 14 having a socket therein for receiving a lamp bulb 15 which is protected by a globe 16 detachably associated with the base member 14 so that access may be had to the bulb for changing the same. The bulb is of course in electrical connection with a suitable source of current, and is controlled by a switch, not shown.

The door is provided with a handle 17 secured to the upper portion of the outer frame member, as shown, and it will be obvious that the transparent panels allow for ready inspection of the contents of the oven without opening the door, especially when the illuminating means is in use.

While the panels are preferably made from glass and are of the kind that is not readily affected by heat, in the event that they should become broken or cracked, they can be readily replaced due to the detachable association of the frame members, as will be obvious upon inspection of Figure 2.

I preferably provide in combination with my

door a light reflecting lining for the oven, such as white metal, porcelain or the like, to aid in illuminating the oven.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. An oven door comprising inner and outer frame members, each including a body portion having an opening therein, outwardly flared rims formed on the outer edges of the body portions and inwardly directed therefrom, said rims being disposed for interfitting association, with the rim of the outer frame member disposed exteriorly of the rim of the inner frame member, transparent panels mounted in the frame mem-

bers for closing the openings, spacing means for the panels, lugs formed on the body portion of the outer frame member and having threaded bores therein, screw means extending through the body portion of the inner frame member and threaded in the bores for securing the frame members together for cooperation with the spacing means for holding the panels in fixed spaced relation to each other, mounting means for the door and secured to the outer frame member, and a handle for the door.

2. An oven door comprising frame means providing openings, transparent panels mounted in the frame means for closing the openings, illuminating means mounted on the inner side of the frame means for illuminating the oven when the door is closed, pintles extending laterally from the frame means for pivotally securing the door in position for use, and a handle secured to the frame means.

MASIE PAUL.
